(57) **CLAIM**

The ornamental design for an earphone charging case as shown and described.

DESCRIPTION

1.1 is a bottom plan view of an earphone charging case of our new design, shown in an open configuration;

1.2 is a front elevation view thereof;

1.3 is a back elevation view thereof;

1.4 is a top plan view thereof;

1.5 is a right side elevation view thereof;

1.6 is a top plan view of the earphone charging case, shown in a closed configuration;

1.7 is a right side elevation view thereof;

1.8 is a left side elevation view thereof;

1.9 is a top perspective view of the earphone charging case, shown in an open configuration;

1.10 is a left side elevation view thereof;

1.11 is a bottom plan view of the earphone charging case, shown in a closed configuration; and,

1.12 is a front perspective view thereof.

The broken lines in the drawings illustrate portions of the article that form no part of the claimed design.

1 Claim, 12 Drawing Sheets
